UNITED STATES PATENT OFFICE.

HENRY HOWARD, OF CLEVELAND, OHIO, ASSIGNOR TO THE GRASSELLI CHEMICAL COMPANY, OF CLEVELAND, OHIO, A CORPORATION OF OHIO.

PRESSURE SULPHUR BURNER.

Application filed March 21, 1927. Serial No. 177,097.

This invention relates to a stationary elemental sulphur burner capable of working against superatmospheric pressures.

An object of the invention is to provide a sulphur burner which is capable of producing a gaseous mixture containing a high percentage of sulphur dioxide gas free from sublimed sulphur, which burner is adapted to working against superatmospheric pressures.

10 Another object of the invention is to provide a sulphur burner which is adapted to deliver sulphur dioxide-containing gas in regulated quantities having a constant sulphur dioxide content.

15 Another object of the invention is to provide a sulphur burner which is simple, efficient and economical in operation and of low construction cost.

I have found that, by introducing regulated predetermined quantities of molten sulphur and an oxygen-containing gas,—as for example air,—under superatmospheric pressure into a suitably constructed chamber adapted to conserve substantially all of the 25 heat of combustion of sulphur, the said heat of combustion may serve to vaporize substantially completely the incoming molten sulphur which, in intimate admixture with the oxygen-containing gas and at the temperature maintained within the chamber, 30 burns very quickly to the formation of a sulphur dioxide-containing gas of constant, predetermined, sulphur dioxide content free from sublimed sulphur in a gas having a 35 sulphur dioxide content not greater than 18%.

The invention will be described and illustrated with reference to the accompanying drawings, in which is shown somewhat diagrammatically one form of apparatus embodying the invention.

Figure 1 is a vertical section of the apparatus, with parts appearing in elevation;

Figure 2 is a broken horizontal sectional view taken on the line 2—2, Fig. 1;

Figure 3 is a broken vertical sectional view taken on the line 3—3, Fig. 1;

Figure 4 is a top plan view of the spiral mixing port 5 of Fig. 1.

50 Referring to the drawings:

The burner comprises a chamber consisting of an air-tight outer cylindrical shell 1 constructed of suitable material, as, for ex-

ample, steel, lined with heat insulating material such as, for example, firebrick 2, and 55 provided with arched partitions 3 and 4 dividing the said chamber into three superimposed compartments A, B and C. The arched partitions 3 and 4 may be constructed of firebrick, but I prefer to make 60 use of a highly heat-conductive refractory material, such as, for example, the material known as "Carbofrax" for the construction of the arched partition 3. 5 is a spiral mixing port located in the center of the arched 65 partition 3, providing a passageway from compartment A to compartment B. Passageways from compartment B to compartment C are provided by a series of ports 6 located around the periphery of the arched 70 partition 4. 7 is a flue in communication with compartment C through the side ports 8, and leading to the exit conduit 9. 10 and 11 are inspection and cleanout ports. 12 is a conduit for the introduction of regulated 75 quantities of air preferably from a positive displacement pump under superatmospheric pressure, into the compartment A, which conduit preferably is positioned tangentially with respect to the burner. The tangential 80 positioning of conduit 12 is not an essential element of the invention, as the spiral mixing port 5 insures thorough mixing of the air and the vaporized sulphur.

13 is a melting tank providing maintenance of a supply of molten sulphur. The melting tank 13 is provided with any suitable means for maintaining sulphur in molten state preferably at maximum fluidity. The heat necessary to maintain the body of sulphur at maximum fluidity conveniently may be obtained by means of saturated steam at 75 to 100 pounds pressure either in a coil or jacket or both (not shown). Means are provided for delivering regulated 85 amounts of molten sulphur into the compartment A, against superatmospheric pressure therein maintained, represented by the opening 14 in the top of the burner, the conduit 15, and the positive displacement pump 16 submerged in the body of molten sulphur contained in the tank 13. This tank preferably is located with its top level with the ground. 17 is an opening in the cover 100 through which the sulphur may be dumped. 105 The top of the burner is heat-insulated by

a sand fill 18. 19 and 20 are aligned manholes in the shell 1 and lining 2, respectively.

In operation the interior of the burner is brought to a temperature at which sulphur vaporizes and molten sulphur in accurately regulated quantity is delivered into compartment A, falling upon the arched partition 3, where it is substantially completely vaporized by the heat of the burner. 5 Co- incidentally air, under superatmospheric pressure, in accurately regulated quantity, is introduced (preferably tangentially) into compartment A through the conduit 12, is mixed with the sulphur vapor therein, and 10 the burning air-sulphur vapor mixture passes through the spiral mixing port 5 in the arched partition 3, where it is given a further mixing which insures its practically complete combustion as it emerges into 15 compartment B. The thoroughly mixed and very hot gases, streaming from the spiral mixing port 5, burn any traces of free sulphur in the compartment B producing a gaseous mixture comprising sulphur dioxide, 20 nitrogen and free oxygen, and thereby generating sufficient heat not only for the substantially complete volatilization of further quantities of molten sulphur delivered upon the heat-conductive arched partition 25 3, but also to provide a considerably larger surplus of heat than is obtained from the commonly used type of sulphur burner, owing to the very small radiation losses due 30 partly to the high rate of combustion and partly to the reduced radiating surface of 35 the burner.

The combustion gases formed in B, especially when very rich in sulphur dioxide and containing a very small excess of oxygen beyond that required to convert the sulphur to sulphur dioxide, may still contain some unburned sulphur vapor. These pass from compartment B through the series of ports 6 into compartment C, where the last 40 traces of uncombined sulphur are burned to sulphur dioxide, provided of course that the requisite oxygen is present. It is a fact that, in ordinary operation, practically all of the combustion of the vaporized sulphur 45 is complete before the gases leave compartment B. Much burning will occur in compartment A, although this serves essentially as the vaporizing and mixing chamber. The combustion gases which are now free 50 from unburned sulphur, pass from compartment C into the flue 7, through the side ports 8, and are conducted to the point of use through conduit 9.

An essential feature in the design of this 60 burner is the downward path given the gases in the combustion chamber,—the hottest gases naturally are those still burning and, as the heat makes them lighter, they rise as high as possible and therefore are automatically kept away from the outlet flue, thereby

forcing the completely burned and relatively cooler gases continuously into the outlet flue.

The particular advantages accruing from the use of this burner are as follows:

1. The air and molten sulphur are introduced into the burner in regulated amounts, and since all the sulphur vaporizes and burns almost instantly, regulated quantities of a sulphur dioxide-containing gaseous 75 mixture are obtained.

2. By the regulation of the relative amounts of air and molten sulphur so introduced, it is possible to obtain a sulphur dioxide-containing mixture having any desired concentration of sulphur dioxide up to almost the theoretical limit possible with air or such other oxygen source as may be used.

3. The substantially complete vaporization of the molten sulphur introduced into compartment A is assured by conserving in the burner the heat generated by the combustion, so that there is very little if any opportunity for a pool of molten sulphur to accumulate upon the arched partition 3. The practically instantaneous vaporization effected by the conserved heat of combustion permits of a uniform and controllable rate of combustion of the sulphur and the consequent production of a uniform and controllable composition of the sulphur dioxide-containing gaseous mixture.

4. The vaporized sulphur is very thoroughly mixed with the air first by admitting the latter tangentially into the mixing chamber under superatmospheric pressure, and second by subjecting the gaseous mixture to an exceedingly thorough mixing action by the passage thereof through the spiral mixing port 5. This thorough mixing greatly shortens the time and correspondingly reduces the space required for the complete combustion of the sulphur.

5. The opportunity for the accumulation of impurities within the burner is slight, in view of the fact that the sulphur is melted before being introduced into the burner and the separation of any impurities contained in the raw material takes place largely in the melting tank 13, which is outside of the burner proper.

6. By the normal operation of this burner there is delivered a supply of sulphur dioxide-containing gas under superatmospheric 120 pressure.

7. A particular advantage is the simplicity and low construction cost of the apparatus, which is free of moving parts within the burner proper.

While, according to the foregoing description, there has been described a particular means for delivering to the burner molten sulphur in regulated quantities, it is to be understood that the invention is not 130

limited thereto, and that any suitable means may be used for delivering regulated quantities of molten sulphur against the pressure maintained in the burner. Also, while it is preferred that the burner be cylindrical in cross-section, it probably could be made in rectangular, square, octagonal, etc., cross-section at no material increase in cost and without materially impairing the efficiency of the burner.

10 I claim:

1. A sulphur burner comprising a vertically disposed, cylindrical, heat-insulated chamber divided by substantially horizontal partitions into at least two compartments, said partitions provided with ports establishing communication between said compartments, the port in the partition forming the bottom of the topmost compartment being a spiral mixing port, a conduit projecting into the topmost of said compartments, means for supplying air under superatmospheric pressure through said conduit, a second conduit entering said topmost compartment, means for supplying molten sulphur through said second conduit, and a gas conduit communicating with the bottom-most of said compartments.

2. A sulphur burner comprising a verti-

cally disposed, cylindrical, heat-insulated chamber divided by two spaced-apart substantially horizontal partitions into an upper mixing compartment, a middle combustion compartment, and a bottom combustion compartment, a spiral mixing port adjacent the center of the upper of said two partitions, a plurality of ports adjacent the periphery of the lower of said two partitions, means for supplying said mixing compartment with a regulated quantity of molten sulphur, means for supplying said mixing compartment with a regulated supply of air under superatmospheric pressure, and a gas outlet from the bottom combustion chamber.

3. A sulphur burner comprising a vertically disposed, heat insulated, pressure resisting chamber having a vaporizing and burning section at the top thereof, at least one combustion section below said vaporizing and burning section, means for introducing air and sulphur under superatmospheric pressure into said vaporizing and burning section and means for withdrawing products of combustion at the bottom of the combustion chamber.

In testimony whereof I affix my signature.

HENRY HOWARD.
